CLAIM

The ornamental design for a kitchen scale, as shown and described.

DESCRIPTION

FIG. 1 is a front elevation view of a kitchen scale in non-service mode, showing my new design;

FIG. 2 is a rear elevation view thereof;

FIG. 3 is a left side view thereof;

FIG. 4 is a right side view thereof;

FIG. 5 is a top view thereof;

FIG. 6 is a bottom view thereof;

FIG. 7 is an alternate front elevation view thereof shown in service mode; and,

FIG. 8 is an enlarged view of portion 9 of FIG. 3.

The dash-dash broken lines in the drawings depict portions of the kitchen scale that form no part of the claimed design. The dot-dash broken lines represent boundaries of the enlarged portions in FIGS. 3 and 8 and form no part of the claimed design.
